SELF-ALIGNING ROTARY ELECTRICAL SWITCH

Donald O. Dulude, Rochester, Mich., assignor to Kuhlman Electric Company, Birmingham, Mich., a corporation of Michigan

Application January 23, 1958, Serial No. 710,734

3 Claims. (Cl. 200—11)

This invention relates to rotary electrical switches and more particularly to a rotary switch construction adapted for use in high potential circuits such as is required of transformer tap changers, for example, and in which the electrically conductive contact parts of the rotor are self-adjustable to assure uniform contact pressure in the event of misalignment of the contact parts with which the rotor mounted contacts cooperate.

Switches of the general class to which the invention relates and in use heretofore customarily include a plurality of stationary contacts connected to selected current-carrying parts of electrical apparatus such as a transformer, for example, and mounted on a supporting panel in arcuate or circular form. Such constructions also include a rotatable bridging device composed of one or more generally segment-shaped plates provided with one or more contact parts, the arrangement being such that the contact part or parts on the bridging device are capable of spanning the distance between and engaging any two adjacent stationary contacts on the panel. In some of the prior switch constructions, the contacts carried by the bridging device have been arranged to straddle a pair of stationary contacts and lie in substantially parallel planes so as to enable magnetic force to add to the mechanical force with which the stationary contacts are gripped by the bridging contacts.

In the known constructions difficulty has been experienced in obtaining uniform contact pressure between the bridging contacts and the two adjacent contacts of the stationary contacts. One of the principal sources of difficulty in this respect is due to misalignment of the stationary contacts, that is, one of the stationary contacts may not be in exactly the same plane as the other. When two such misaligned contacts are bridged by the bridging contacts, considerably more pressure will be exerted on one stationary contact than on the other, with the result that excessive wear of the contacts occurs, or infirm engagement is obtained between the bridging contacts and one of the stationary contacts, or both.

An object of the invention is to provide a rotary switch construction which overcomes the disadvantages previously referred to of switches in use heretofore.

Another object of the invention is to provide a rotary switch construction in which the stationary and bridging contact elements are so constructed and arranged as to be capable of relative movement so as to compensate for misalignment of the stationary contacts.

A further object of the invention is to provide a self-aligning rotary switch construction in which the stationary and movable contact elements are capable of substantially universal relative movement within limits so as automatically to assure uniform contact pressure of the movable and stationary contact elements.

Still a further object of the invention is to provide a rotary switch construction of the kind referred to in which the movable bridging contacts are arranged to straddle the stationary contacts and are yieldably urged

2

towards one another so as to grip the stationary contacts therebetween.

Other objects and advantages of the invention will be pointed out specifically or will become apparent from the following description when it is considered in conjunction with the appended claims and the accompanying drawings, in which:

Figure 1 is a view partly in plan and partly in section of the elements of a rotary switch constructed and arranged in accordance with one embodiment of the invention;

Figure 2 is a fragmentary, enlarged elevational view of the apparatus shown in Figure 1;

Figure 3 is an end elevation of one of the movable contact elements supported on its rotor part in accordance with the invention;

Figure 4 is a view similar to Figure 1, but disclosing a modified form of the invention; and

Figure 5 is a fragmentary, enlarged view partly in elevation and partly in section of the construction shown in Figure 4.

Apparatus constructed in accordance with the embodiment of the invention shown in Figures 1 and 2 comprises a mounting panel 1 formed of any suitable insulating material such as laminated nylon, phenolic material such as "Bakelite," or any other suitable substance, and on which is mounted a plurality of stationary contact elements 2 formed of suitable electrically conductive material such as copper. As is best shown in Figure 1, the contact elements 2 are arranged in arcuate or circular form and each of the contact elements is mounted on the panel 1 by means of a metallic, headed bolt 3 and an annulus or ring 4 formed of the same material as the mounting panel 1. Each of the contact elements 2 and the annulus 4 are provided with aligned openings to accommodate the shanks of the bolts 3, the headed ends of the bolts bearing against the respective contacts 2 and the other end of the bolts being threaded as at 5 for reception of retaining nuts 6. One end of a current-carrying part 7 leading from a transformer or the like (not shown) also may be connected to each bolt 3 and removably anchored to the latter by an anchor nut 8, whereby the part 7 is electrically connected to the associated contact element 2. Each of the contact elements 2 may have a blind opening 9 therein adapted to register with a similar opening 10 formed in the annulus 4, the openings 9 and 10 normally receiving an anchor pin 11 which reacts between the contact element 2 and the annulus 4 to prevent rotation of the contact element about the axis of the bolt 3.

At the center of the arc or circle defined by the several contact elements 2 the mounting panel 1 may be provided with an opening 12 in which is rotatably mounted a driving shaft 13 which preferably is formed of insulating material similar to that previously referred to. Suitable means such as a crank or wheel (not shown) may be fixed at one end of the driving member 13 for rotating the latter when desired.

In the embodiment of the invention disclosed in Figures 1 and 2, the switch includes a bridging device 14 composed of a pair of supporting members or plates 15 formed of non-conductive material of the kind previously referred to and spaced apart from each other. Each of the mounting plates 15 is cut away at one end as at 16 so as to form a pair of leg sections 17 adapted to straddle the driving shaft 13. The leg section 17 of each supporting plate is provided with aligned openings 18 adapted for reception of either a metallic or non-metallic mounting pin 19 which also passes through an opening in the driving shaft 13 so as rockably to connect each mounting plate 15 to the driving shaft for movement with the latter. The

size of the openings 16 and the locations of the pin-receiving openings 18 are such that, in assembled relation, there is a gap 20 between the drive shaft 13 and the inner wall of the opening 16 so as to enable each plate 15 to partake of limited rocking movement about the axis of its pin 19. If desired, the retention of the pin 19 may be assured by a tapered or other suitably constructed locking pin 21 extending through openings in one leg 17 of each mounting plate 15 and in the pin 19, the latter opening being located at right angles to the opening 18.

The supporting members 15 are so connected to the drive shaft 13 that they are superposed and extend radially from the drive shaft towards the arc or circle defined by the stationary contact elements 2. The radially outermost end of each of the mounting plates 15 is provided with an extension or ledge 22 which projects beyond the remainder of the plate 15 and the outer face of each plate 15 is bored as at 23 for reception of one end of a mounting post 24. Adapted to be mounted on the radially outer end of each mounting plate 15 is a bridging contact member 25 formed of suitable electrically conductive material such as copper and each contact member 25 is provided with a substantially centrally located bore 26 of such size as rotatably to receive the shank of the mounting post 24. The outer end of the post 24 is headed as at 27 so as to prevent inadvertent separation of the contact member 25 and the associated mounting plate 15 and the mounting post 24 is removably retained in assembled relation with its associated mounting plate 15 by means of an anchor pin 28 which extends through aligned openings in the mounting plate and the mounting post 24. The size and arrangement of each of the contact members 25 are such that a small gap 22a exists between the member and its associated ledge 22 when the parts are assembled. The gap 22a permits each contact 25 to be rocked about the axis of the post 24, for a purpose to be pointed out, and the rockable mounting of the contacts 25 and the supporting plates 15 enables each contact to partake of substantially universal, but limited movement.

The spacing of the two mounting plates 15 during normal operating conditions is such that the two adjacent contact elements 2 bridged by the contact members 25 are sandwiched between the latter as is shown in Figure 2. In the preferred construction each of the mounting plates 15 is rockable about the axis of its associated mounting pin 19, as has been pointed out, so in order to assure good contact between the stationary contact elements and both bridging contact members 25, yieldable means generally indicated by the reference character 29 is incorporated in the apparatus for yieldably biasing the mounting plates 15 and the contact members 25 towards one another. The biasing means disclosed in Figures 1 and 2 may comprise a bolt 30 extending through aligned openings 31 in the mounting plates 15 and having a head 32 at one end adapted to bear against one of the plates 15. The bolt 30 may receive a washer 33 adjacent to its other end arranged to bear against the other mounting plate 15 and the bolt also receives a spring 34 arranged to react between the washer 33 and a similar washer 33a which may be adjusted longitudinally of the bolt by a threaded nut 35. Adjustment of the nut 35 on the bolt 30 will vary the force with which the mounting plates 15 and their associated contacts 25 are urged towards one another.

In the operation of the embodiment disclosed in Figures 1, 2 and 3, the driving shaft 13 may be rotated so as to cause the contacts 25 to bridge any two adjacent stationary contacts 2 and engage the latter on opposed surfaces as is shown in Figure 2. In an ideal construction, the opposed surfaces of the stationary contacts 2 will be perfectly parallel with each other and with the surface 1a of the mounting panel 1. In actual practice, however, the opposed surfaces of the stationary contacts 2 may not be parallel with each other or with the adjacent surface of the mounting panel, and the stationary contacts 2 of any given pair of contacts may be somewhat misaligned so

that they are not located in the same place. In either event, firm contact between the bridging contacts 25 and any two adjacent stationary contacts 2 is assured, due to the ability of each contact 25 to rock about the axis of its mounting post 24 which, as is best illustrated in Figure 2, lies in a plane substantially parallel to the plane of the surface 1a of the longitudinal panel 1. Positive engagement between the bridging contacts and the stationary contacts further is assured by the yieldable biasing means 29. As a result, good electrical connection between two adjacent stationary contacts 2 is provided.

Rotary switches of the kind to which the invention relates generally are manufactured carefully, so the misalignment of any two adjacent stationary contacts 2 usually will be of fairly small degree. Accordingly, the degree of rocking movement of the movable contacts 25 and the plates 15 need not be great. However, the sizes of the gaps 20 and 22a may be as large as necessary to produce the desired results.

In order to assure smooth operation of the switch when the bridging device is rotated, the ends of the contacts 25 are rounded as at 25a to permit them to ride smoothly over the fixed contacts 2 in either direction of rotation of the drive shaft 13. The contacts 25 also may be rounded as at 25b to avoid the concentration of voltage stresses.

The embodiment of the invention disclosed in Figures 4 and 5 is generally similar to the embodiment previously described, with the exception of the construction of the plates on which the movable contact elements 25 are mounted. In the modified embodiment of the invention each of the mounting plates 15a is provided with a substantially elliptical opening 16a having its major axis lying along the longitudinal axis of the plate 15a so as to provide a gap 20a between the plate 15a and the driving shaft 13, thereby enabling each plate 15a to rock about the axis of the mounting pin 19 in a manner similar to the embodiment previously described. Figures 4 and 5 also disclose a modified form of biasing means 29a for yieldably urging the contacts 25 towards one another and which comprises a shouldered pin 30a having a reduced end portion 35' received in an opening 36 in one of the plates 15a and an enlarged portion 35a received in an opening 37 in the other plate 15a. Surrounding the pin 30a between the plates 15a is a spring 38 which bears against each of the plates 15a and urges them in such directions as to cause the contacts 25 to move towards one another and grip the stationary contact elements 2 sandwiched therebetween. Retention of the pin 30a may be assured by peening over the free end of the reduced end portion 35 as is indicated at 35b.

In the construction shown in Figures 4 and 5 the structure and arrangement of the mounting plates 15a and the yieldable means 29a are such that the driving shaft 13 is interposed between the yieldable means and the bridging contacts 25, whereas in the embodiment of the invention shown in Figures 1 and 2 the construction and arrangement of the mounting plates 15 and the yieldable means 29 are such that the yieldable means is interposed between the drive shaft 13 and the movable contacts 25. In all other respects, however, the two embodiments are similar and the operation of the two embodiments is identical.

Apparatus constructed in accordance with either embodiment of the invention not only has the desirable characteristics referred to above, but also possesses the advantages of known constructions. For example, the contact members 25 are maintained in substantial parallelism so as to enable the magnetic forces created by current passing therethrough to add to the mechanical force by which the stationary contacts are gripped. Furthermore, backlash is not required to obtain the self-aligning action of the contacts 25. Moreover, all electrical energy carrying parts are isolated by insulating material and are supported in spaced relation to the mounting panel 1 so as to minimize the formation of sludge. An addi-

tional advantage of the disclosed embodiments is the ability of the apparatus to be made of such small size as to be mounted in an insulated tube, thereby allowing the unit to be nested between the coils of a transformer.

The disclosed embodiments are representative of presently preferred forms of the invention, but are intended to be illustrative rather than definitive thereof. The invention is defined in the claims.

I claim:

1. A rotary switch construction comprising a mounting panel; a plurality of electrically conductive contact elements; means mounting said contact elements on said panel in spaced apart, arcuate form and spaced from said panel; a rotary driving element located at the center of the arc defined by said contact elements; a pair of spaced apart, superposed, generally parallel support members formed of insulating material and extending radially from said driving element towards the arc defined by said contact elements; pivotal means drivingly mounting each of said support members on said driving element for rotation with the latter about the axis of rotation of said driving element and for movement of the radially outer ends of said support members towards and away from one another about spaced axes defined by their respective pivotal means; an elongate, electrically conductive contact member for each of said support members and being of such length as to bridge the space between and engage opposite sides of any adjacent two of said contact elements; pivotal means mounting each of said contact

members on its respective support member adjacent to the radially outer end thereof for rotation about an axis substantially parallel to and fixed with respect to its respective support member; limit means on each of said support members cooperable with said contact members for limiting rotation of the latter; and yieldable means reacting on said support members remote from said contact members for yieldably urging the radially outer ends thereof and said contact members towards one another.

10 2. The construction set forth in claim 1 wherein said yieldable means reacts intermediate said driving element and the radially outer ends of said support members.

3. The construction set forth in claim 1 wherein said 15 supporting members include extensions projecting from the axis of rotation of said driving element in a direction opposite from said radially outer ends, and wherein said yieldable means reacts on said extensions.
